UNITED STATES PATENT OFFICE.

HEINRICH WULKAN, OF BUDAPEST, AUSTRIA-HUNGARY, ASSIGNOR TO DEXTRIN AUTOMAT, GESELLSCHAFT M. B. H., OF VIENNA, AUSTRIA-HUNGARY, A CORPORATION OF AUSTRIA-HUNGARY.

PROCESS FOR MOISTENING AND COOLING DEXTRIN.

1,139,621.

Specification of Letters Patent.

Patented May 18, 1915.

Application filed August 13, 1913. Serial No. 784,635.

To all whom it may concern:

Be it known that I, HEINRICH WULKAN, a citizen of the Empire of Austria-Hungary, residing at Budapest, in the Empire of Austria-Hungary, have invented a new and useful Improvement in Processes for Moistening and Cooling Dextrin, of which the following is a specification.

This invention relates to a process and apparatus for moistening and cooling dextrin; and it comprises a process of moistening and cooling dextrin which comprises subjecting the dextrin while maintained in a state of constant agitation to the action of a mixture of steam and air or of supersaturated air while maintained at a temperature below about 60° C. and particularly between 40° to 50° C. by means of a cooling medium which is kept from direct contact with the dextrin itself; and it also comprises an apparatus in which provision is made for the introduction of a mixture of air and steam or of supersaturated air together with agitating means for agitating the dextrin and means for cooling the dextrin without direct contact of the cooling medium with the dextrin being treated; and it further comprises certain novel features of construction and arrangement of parts and certain novel features of the process; all as more fully hereinafter set forth and as claimed.

In the moistening of dextrin it is difficult to prevent the formation of a thick viscous mass which is difficult to handle and which is frequently also difficult to convert into thinner so-called solutions of dextrin such as are used in the arts. Since dextrin is usually soluble in water it is usually necessary to keep it entirely free from moisture until such time as it is desired for use. According to the process of the present invention, it is possible to moisten dextrin without the formation of such a thick gummy mass so that the moistened dextrin still retains its finely divided powder form, in which form it can be readily kept and subsequently utilized by the addition of further water or in other suitable manner. The

presence of the added water in the powdered or finely divided dextrin makes this material a particularly valuable material for subsequent use, containing as it does the added moisture in an unobjectionable form, and being capable of use without the necessity for the subsequent addition of as large amounts of water as would otherwise be necessary, and resulting in smooth and homogeneous solutions.

In carrying out the process of the present invention, the dextrin is maintained in a state of constant agitation and is treated with a mixture of steam and air or supersaturated air while maintained at a suitable temperature. The mixture of steam and air or the supersaturated air can be prepared by injecting direct steam into a current of compressed air, or by conducting air through a vessel in which steam is formed or is introduced, or a current of air may be sucked in by a steam injector; or other suitable means for forming the mixture of steam and air or the supersaturated air can be used. After the dextrin is cooled to a temperature below 60° C. and advantageously below 50° C. the mixture of steam and air is slowly introduced into the agitated dextrin and the temperature of the dextrin is maintained at about 40° to 50° C. during the introduction. During the introduction of the steam, or of the hot supersaturated air and in order to avoid the tendency toward increase in temperature due to the temperature of the entering steam, the dextrin is kept in lively motion and subjected to an energetic cooling so that the specified temperatures are not exceeded. The cooling of the dextrin is not effected by the introduction of the cooling medium through the dextrin, but is effected by external cooling of the vessel in which the dextrin is contained, the cooling being effected by cold air which is in turn cooled by cold water.

In the accompanying drawings which illustrate the present invention is shown an apparatus in which the process of the present invention can be carried out. In this apparatus the vessel A is shown as provided

with a stirrer B driven by means of bevel gears M and the pulleys N. In the bottom of the vessel A is a false bottom C which is provided with a large number of small perforations and which forms a sieve through which the mixture of air and steam can pass. Surrounding the vessel A are the two jackets D and E and through the outer jacket E provision is made for the circulation of cold water which enters at c and escapes at d, while through the inner jacket D air is circulated, entering at a and being discharged at b. A steam injector is shown at F into which high pressure steam is admitted through e and into which the air outlet b also discharges. The injector discharges through the 3-way valve f by means of which the mixture of air and steam can be either discharged to the atmosphere or admitted in any desired amount to the bottom of the chamber A below the false bottom C. An outlet g is provided from the bottom of the chamber A and communicating with the steam and air mixture inlet pipe for carrying away any condensed steam from the apparatus. The chamber A is provided with an opening H for charging and an opening I for discharging, and is also provided with a hood G in the top of which is a filter h, and with a thermometer m for indicating the temperature of the apparatus. In the operation of this apparatus and in practising the process of the present invention in it, the dextrin is charged into the apparatus through the opening H and is constantly agitated by means of the stirrer B. Cold water is circulated through the outer casing E and air is drawn through the inner jacket and out through the outlet b by means of the steam injector F. If the temperature of the dextrin is higher than about 40° to 50° C. then air is sucked through the inner jacket and out through the outlet b by means of the steam injector F and the mixture of steam and air or the supersaturated air is allowed to escape to the atmosphere through the 3-way valve f until the temperature has been reduced to about 40° to 50° C. which is the temperature found to be particularly advantageous in carrying out the process. When this temperature has been reached, the cock f is turned to admit the mixture of steam and air into the bottom of the casing from which it passes up through the perforated false bottom or sieve C into the dextrin which is constantly agitated and constantly cooled. The amount of the mixture of steam and air and the rate of cooling can be controlled by means of the steam injector f and the 3-way valve, any excess of the steam and air mixture being permitted to escape to the atmosphere during the process. By suitable regulation of

the injector and the amount of the steam and air mixture or the degree of supersaturation of the air introduced into the apparatus, the dextrin can be maintained at the temperatures specified throughout the process until the desired moistening has been effected. While other means for cooling dextrin might be utilized, yet it has been found that the method described and illustrated by the drawing has been found advantageous. Any steam which may condense and separate out in the apparatus or in the inlet pipe will find its way out through the condensed water outlet g. The hood G and the filter h prevent the dextrin from escaping with any escaping current of air.

By the process and apparatus of the present invention it is possible to moisten the dextrin and obtain a moistened dextrin without the formation of a thick or sticky gum and without the use of temperatures such as would injuriously affect the dextrin or result in its modification. The moistened but still finely divided dextrin is a particularly valuable product, as already indicated.

In carrying out the process of the present invention it is essential that the dextrin be subjected to the necessary cooling in order that its temperature may not rise above from 40° to 50° C. or a maximum of about 60° C.

I claim:—

1. The process of moistening dextrin which comprises subjecting the dextrin while maintained in a state of agitation to the action of heated supersaturated air and to the action of a cooling medium sufficient to maintain the temperature of the dextrin below about 60° C. without direct contact of the cooling medium with the dextrin treated.

2. The process of moistening dextrin which comprises subjecting the dextrin while maintained in a state of agitation to the action of heated supersaturated air and to the action of a cooling medium sufficient to maintain the temperature of the dextrin between 40° and 50° C. without direct contact of the cooling medium with the dextrin treated.

3. The process of moistening dextrin which comprises maintaining the dextrin in constant agitation in a vessel maintained by external cooling means at a temperature between 40° and 50° C. and introducing into the dextrin while so cooled and agitated a heated supersaturated air mixture in regulated amounts.

4. The process of moistening and cooling dextrin which comprises subjecting the dextrin to agitation in a vessel provided with means for circulating externally thereof a current of a gaseous cooling medium, circulating therethrough such gaseous cooling

medium until the temperature of the apparatus is about 40° to 50° C., mixing the resulting cooling medium with steam, and subjecting the dextrin while so cooled and agitated to the action of the resulting mixture of steam and gaseous cooling medium.

In testimony whereof I hereunto set my

hand in the presence of two subscribing witnesses.

HEINRICH WULKAN.
